UNITED STATES PATENT OFFICE.

AUGUST M. ANDERSON, OF MOORHEAD, MINNESOTA.

EXCAVATOR.

No. 818,215.

Specification of Letters Patent.

Patented April 17, 1906.

Application filed May 11, 1905. Serial No. 259,862.

To all whom it may concern:

Be it known that I, AUGUST M. ANDERSON, a citizen of the United States, and a resident of Moorhead, in the county of Clay and State of Minnesota, have invented a new and Improved Excavator, of which the following is a full, clear, and exact description.

This invention relates to excavators such as used in railroad construction-work, repairing road-beds, and in the construction of ditches and irrigating-canals. It is also useful for clearing a roadway of ice, snow, or similar obstruction.

The invention consists in the construction and combination of parts to be described more fully hereinafter and definitely set forth in the claims.

Reference is to be had to the accompanying drawings, forming a part of this specification, in which similar characters of reference indicate corresponding parts in all the figures.

Figure 1 is a side elevation of the machine. Fig. 2 is a plan. Fig. 3 is a vertical section taken substantially upon the line 3-3 of Fig. 2. Fig. 4 is a plan of the lower portion of the mechanism, certain parts being shown in section and broken away, as will appear. Fig. 5 is a vertical section taken substantially upon the line 5-5 of Fig. 3. This view is upon an enlarged scale, as will appear. Fig. 6 is a horizontal section through a cutter or excavating-wheel and the contiguous parts, the same being represented as broken away and upon an enlarged scale; and Fig. 7 is a transverse section through a portion of the wheel shown in Fig. 6.

Referring more particularly to the parts, 1 represents the frame of the machine. This frame comprises a pair of parallel beams 2, disposed longitudinally of the machine, as indicated. Near the forward portion of these beams bearings 3 are provided, in which a transverse shaft 4 is mounted. Upon the extremities of this shaft 4, which project beyond the beams 2, as shown, forwardly projecting arms 5 are attached. The projecting extremities of the shaft 4 are preferably braced by suitable diagonals or struts 6. The arms 5, referred to above, consist, preferably, of flat bars which project in a parallel relation and forwardly with respect to the implement in the manner shown. Their forward extremities are preferably sharpened, 55 as shown in Fig. 4, so as to present cutting

edges 7, the purpose of which will appear more fully hereinafter. The arms 5 are substantially horizontal, as shown, and they support between them a cutter or excavating-wheel 8, the construction of which will be described more fully hereinafter. Behind this excavating-wheel 8 a plow 9 is arranged, the same being attached to the arms 5 by removable keys 10. This plow 9 is mounted at the forward extremity of a plow-frame, 65 which frame comprises beams 11, which are disposed in an inclined relation, as indicated in Fig. 1, being pivotally attached at their extremities to brackets 12, carried on the under sides of the main beams 2 of the frame 1. The forward portions of these beams 11 are supported upon hangers 13, which also are disposed in an inclined relation and attached pivotally at 14 to the rear portion of the plow. Their upper extremities attach 75 pivotally to brackets 15, which are carried by the forward extremities of the beams 2 aforesaid.

The machine is supported upon driving-wheels 16, disposed toward the rear of the 80 implement, as indicated in Fig. 1, and forward of these wheels steering-wheels 17 and 18 are arranged, as shown. The wheels 16 are carried upon a fixed axle 19, which is attached to the under side of the frame 1, as indicated. The wheels 17, which are intermediate in size and also in position, are carried upon an axle 20, which is mounted upon a pivot-pin 21 at its central point, as indicated in Fig. 4. The forward wheels 18 are carried 85 upon an axle 22, which is mounted upon a pivot-pin 23, as shown, and this axle is carried at the under sides of the forward portion of the plow-beams 11. In order to enable the center of the axle to be supported, the beams 90 are connected at this part by diagonal cross-braces or struts 24.

Near the rear portion of the machine a boiler 25, preferably of locomotive type, is supported upon the frame, and this boiler assists in supporting a superstructure 26, the forward portion whereof is supported upon standards 27, as shown in Fig. 1.

At the rear of the plow 9 a conveyor or elevator 28 is arranged, the same comprising an inclined body 29, the upper extremity whereof is supported adjustably upon hangers 30, the upper extremities of the said hangers being supported in the superstructure 26. Upon the body 29 of the elevator a plurality 110

of rollers 31 are arranged, and at the extremities of the body 29 guide-rollers 32 are provided, around which a continuous conveyer or belt 33 passes. This conveyer or belt 33 has attached thereto a plurality of buckets 34, which are adapted to receive excavated material from the wheel 8 and elevate the same, as will be readily understood. In this connection the purpose of the rollers 31 will appear as they support the full buckets as they are elevated, operating upon the under side of the belt, so as to prevent the sagging between the end rollers. This elevator, as indicated most clearly in Fig. 2, is preferably formed in two opposite parallel sections 28^a and 28^b; but these sections are identical in construction. They are separated by a space which facilitates the transmission of power to the excavating-wheel 8 in a manner which will be described more fully hereinafter.

To the rear of the conveyer 28 and near its upper extremity I provide lateral conveyers 35 for ejecting the excavated material. Referring especially to Fig. 5, these conveyers 35 comprise bodies 36, which are supported pivotally at 37 at their inner extremities upon a suitable framing 38. Near their outer extremities the bodies 36 are supported upon hanger 39, which are attached pivotally at their upper extremities to the superstructure 36. Near their lower extremities these hangers 39 are provided with a plurality of openings 40, which enable the lateral conveyers to be supported in various adjusted positions, as will be readily understood. Like the conveyer 28, the conveyers 35 comprise endless belts, (indicated by the numerals 41,) the same passing around guide-rollers 42 at the ends of the conveyers and carrying a plurality of buckets 43. The inner portions of the belts 41 are preferably supported upon rollers 44, carried by the bodies 36 of the conveyers, as indicated, the function of these rollers being substantially the same as that of the rollers 31 described in connection with the conveyer 28. It should be understood that the conveyers 35 are intended to receive the excavated material from the conveyer 28 and advance the same to be dumped into carts or at the sides of the cut which is being formed. In this aspect the lateral conveyers may be considered as auxiliaries, while the conveyer 28 may be considered the main conveyer.

Arrangement is made for raising the excavating-wheel 8 when the wheel is not being operated. For this purpose upon the superstructure 26 a shaft 45 is provided, which is horizontal in position and disposed transversely of the frame, as indicated most clearly in Fig. 2. Near its extremities this shaft carries loose drums 46, controlled by clutches 47. Upon the drums 46 cables 48 wind, and these cables pass forwardly, as shown, passing over guide-pulleys 49, and they have their

extremities attached to the forward portions of the arms 5, as indicated in Fig. 1. It should be understood that the shaft 45 may be rotated when desired, and thus affords means for raising and lowering the arms 5 and the excavating-wheel 8 when desired. The means for driving this shaft 45 will be described more fully hereinafter. In this connection it should be understood that before raising the arms 5, as suggested, the keys 10 will be removed, so as to disconnect the arms from the plow.

The means for driving the machinery will now be described.

Referring especially to Figs. 3, 4, and 5, an engine 50 of any suitable construction is provided near the forward portion of the boiler, as shown. This engine is preferably of the type illustrated, comprising two cylinders 51 and cranks 52, which are set at right angles upon a horizontal shaft 53. The shaft 53 is provided with a gear-wheel 54, which meshes with a gear-wheel 55, which is rigidly carried upon the aforesaid shaft 4. Upon the shaft 4 there is rigidly mounted a chain-wheel 56, over which passes a chain 57, and this chain 57 passes forwardly and passes around the central portion of the excavating-wheel 8, operating to rotate this wheel in a forward direction, as will be readily understood. The construction of the wheel 8, which enables such an arrangement, will be described presently. The conveyer 28 is driven from its lower extremity, as indicated in Fig. 3, at which point a sprocket-wheel 58 is provided, over which a chain 59 passes. This chain 59 passes rearwardly, as shown, and is driven from an auxiliary shaft 60, disposed below the aforesaid shaft 4, being driven from said shaft by gear-wheels 61, as indicated in Fig. 3. Above the engine-shaft 53 an auxiliary shaft 62 is provided, which affords means for driving the auxiliary conveyers 35. Referring especially to Fig. 5 in connection with Fig. 3, the inner extremities of these conveyers 35 are provided with bevel-gears 63, which are rigidly mounted upon the rollers 42 aforesaid. These bevel-gears 63 mesh with a double bevel-gear-wheel 64, which is disposed between them, as indicated, and the central portion of this bevel-gear 64 constitutes a sprocket-wheel receiving a chain 65. This chain 65 is driven from a sprocket-wheel 66, carried by the aforesaid shaft 62. The gear-wheel 54, it should be understood, is not carried rigidly by the shaft 53, but may be so by operating the clutch 67, as indicated in Fig. 4.

Arrangement is made for enabling the machine to develop its own traction in moving from place to place. For this purpose the engine-shaft 53 is provided with bevel-gears 68, from which a longitudinal shaft 69 leads rearwardly. A clutch 70 enables the gears 68 to be thrown in or out of operation, as will be readily understood. Through bevel-gears 130

71 the shaft 69 operates a counter-shaft 72, which in turn, through the gears 73, as shown in Fig. 4, operates a pinion-shaft 74, the pinion whereof meshes with the main gear-wheels 75, formed within the bodies of the driving-wheels 16. As indicated most clearly in Fig. 3, the engine 50, together with the contiguous clutches and other mechanism, is inclosed in a suitable casing 76. Likewise the chains 57 and 59 are inclosed, respectively, in casings 77 and 78. Arrangement is made for driving the aforesaid shaft 45 by the engine-shaft. For this purpose the engine-shaft is provided with a sprocket-wheel 79, as indicated in Fig. 4, which operates to drive a chain 80, (shown most clearly in Fig. 3,) the said chain passing around guide-pulleys 81, arranged as shown, which enable the chain to be led upwardly to a sprocket-wheel 82, carried by the shaft 45, as will be readily understood. In connection with the sprocket-wheel 82 a clutch 83 is arranged, which enables the sprocket-wheel to be connected or disconnected with the shaft 45, as will be readily understood.

In order to enable the machine to be guided or steered as it advances, I provide a steering-wheel 85, as shown in Fig. 3, which is mounted upon a shaft 86 at the side of the boiler 30 near the rear and in a convenient position to be reached from the firemen's platform 87. As shown in Fig. 1, this shaft 86 extends forwardly and makes a universal connection 88 with a second shaft 89. This shaft 89 makes 35 a connection through bevel-gears 90 with a screw 91. The nut of this screw 91 is rotated when the hard-wheel 85 is turned and operates to move the screw 91 bodily, as indicated in Fig. 4, transversely of the machine. 40 To the extremities of the screw 91 a steering-cable 92 is attached by swivel connections 93, and this steering-cable leads forwardly at each side of the machine and attaches to the axles 20 and 22, the forward extremity of the 45 cable being passed around a guide-sheave 93 near the rear of the plow. From this arrangement, evidently, when the screw 91 moves in either direction it will take up the slack of the steering-cable at one side of the 50 machine and pay it out at the other, in this way operating to change the direction of the machine as it advances.

Recurring again to the excavating-wheel 8 and the manner of guiding the same, it 55 should now appear that the arrangement of the main conveyer 28 in sections is useful in enabling the operating-chain 57 to pass forwardly to the excavating-wheel. The construction of the excavating-wheel 8 will now 60 be described more in detail. Referring especially to Figs. 6 and 7, the wheel is supported upon a shaft 94, disposed transversely between the arms 5 and supported therein, as indicated. At the openings through which 65 this shaft 94 passes the arms 5 are preferably

recessed or offset inwardly, as indicated, so as to present bosses 95 on their inner faces. Over the shaft 94 an elongated sleeve 96 is rigidly mounted, the extremities whereof abut against and are securely held by the 70 bosses 95. This sleeve 96 is securely clamped in this manner by means of a nut 97, mounted upon the threaded extremity of the shaft 94, as indicated. The body of the wheel 8 is composed of an outer rim 98 and an inner 75 rim 99, arranged concentrically, as shown, and of cylindrical form. These rims are rigidly carried upon spokes 100, which radiate from the central shaft 94 and are formed, preferably, in sets, said sets being carried, respectively, by hubs 101, rotatably mounted upon the sleeves 96, as will be readily understood. These hubs 101 are preferably provided with bushings 102 at their bores, as shown. The rims 98 and 99 do not extend 80 continuously from end to end of the wheel, but are arranged in sections *a* and *b*, as shown. Between the adjacent extremities of the sections *a* and *b* a sprocket-wheel 103 is arranged, the same being centered in position by radially-projecting arms 104, the extremities whereof are fixed to the rims. The aforesaid chain 57 passes around this sprocket-wheel 103 and affords means for transmitting 85 a rotary movement to the wheel-rims, as will 95 be readily understood. The central portion of the sprocket-wheel 103 is preferably provided with an enlarged bore 105, through which the sleeve 96 passes loosely, as shown. The ends of the wheels are preferably closed 100 by fixed disks or heads 106, which are provided with centrally-disposed openings 107, which receive the ends of the sleeve 96, as indicated. These heads are set into rims, as shown, the outer faces of the heads being substantially flush with the edge of the outer 105 rim, as indicated. At suitable points the heads 106 are provided with manholes closed by covers 108, as illustrated in Fig. 1, and these covers are adapted to be opened in order to 110 give access to the interior of the wheel for the purpose of replacing or repairing the knives or teeth 109. The form of these teeth 109 is very clearly shown in Fig. 6. They have 115 strut-like bodies 110, which project and curve forwardly, as shown. These bodies are formed with integral shanks 111, which pass through oval openings 112 in the outer rim, as shown, the bodies of the teeth being preferably provided with shoulders 113, adapted 120 to set against the outer rim, as indicated. The shanks 111 terminate in threaded stems 114, which pass through the inner rim and receive nuts 115 for the purpose of securing the teeth, as will be readily understood. The 125 outermost teeth 109, as indicated in Fig. 6, preferably have their bodies enlarged laterally, so that their outer edges are substantially flush with the ends of the wheel. Where the machine is making light cuts, it 130

may be advanced by its own traction; but under ordinary circumstances it may be advanced by cables. For this purpose upon the superstructure 26 at a suitable point 5 there is mounted a feed-drum 116, as indicated most clearly in Fig. 2, the shaft of said drum being provided with a gear-wheel 117, which meshes with a gear-wheel 118, carried by the aforesaid shaft 45. From the drum 10 cables 119 lead forwardly to an anchor planted in the ground or to a tree which is found in a convenient position. It will be remembered that the engine 50 affords means for driving the shaft 45, and hence it also affords means for advancing the implement 15 through the medium of the cable 119.

Arrangement is made for supporting the plow 9 in an elevated position. For this purpose the aforesaid hangers 13 are provided 20 with auxiliary openings 120, as indicated in Fig. 1, and the bolts 121, which attach the upper extremities of the hangers to the brackets 15, are made removable. This arrangement is adopted in order to facilitate the 25 movement of the machine from place to place, operating, as it does, to place the plow at a safe distance above the ground-line.

Referring again to the casing 76, which 30 envelops the principal portion of the machinery, and especially to Fig. 5, it should be stated that the casing is formed into a shield 122, which is disposed above the double bevel gear-wheel 64 at the rear of the main conveyer in such a way as to exclude the excavated material from the gear-wheels. This 35 shield, as indicated in Fig. 5, preferably presents substantially the form of an inverted V in section.

The mode of operation of the implement 40 will now be described. This operation will be most clearly understood from an inspection of Figs. 1 and 3. The power of the engine is transmitted through intermediate mechanism to the chain 57, which chain operates to rotate the excavating-wheel 8 in a 45 forward direction. As this wheel rotates, its teeth 109 dig into the earth in advance of the machine and reduce it to a more or less finely divided condition. The excavated material 50 passes back over the plow 9 and is delivered to the lower extremity of the main conveyer 28. Thence it passes upwardly and is delivered upon the inner extremities of the auxiliary conveyors 35, from which conveyors the 55 material is moved outwardly and delivered at the side of the machine either upon the ground or into a wagon for hauling the material away. Under normal conditions, as suggested above, the machine will be advanced 60 by rotating the feed-drum 116, which drum is driven through the medium of the chain 80 from the engine-shaft. The arrangement of the cable 119 will be suited to the peculiar conditions, enabling the machine to be advanced at a greater or less speed, as may be 65

required. Where the cut to be taken is a shallow cut, enabling the machine to advance at a high rate of speed, the feed-cables 119 may be dispensed with and the machine may be advanced directly by its own traction. When this method is adopted, connection will be made, through the medium of the clutch 70 and the shaft 69, with the driving-wheels 16. When it is desired to move the machine to a new location where excavating-work is to be done, the shaft 45 will be operated from the engine, so as to rotate the drums 46. These drums, it will be remembered, carry the hoisting-cables 48, which lead down to the arms 5, and in this way the 75 arms and the excavating-wheel 8 may be raised to any height desired. Before raising the wheel, however, the arms 5 should be disconnected from the plow by removing the keys 10. In order to afford means for raising 80 the forward part of the frame of the machine in moving it to a new point of operation, as suggested, the wheels 17 and 18 will be removed and replaced in an opposite relation, the wheels 17 taking the places of the wheels 18. When this has been done the wheels 18 will of course be held above the ground-line and the entire weight of the machine will be taken upon the wheels 16 and 17. In order 85 to effect this change of the wheels, an ordinary jack or jack-screw would be employed at the front of the frame. When the excavating-wheel 8 is making an unusually deep cut, the arms 5 will assist in cutting their way through the earth by reason of their 90 sharpened forward edges, which have been referred to above.

Having thus described my invention, I claim as new and desire to secure by Letters Patent—

1. In an excavator in combination, a wheel having teeth, means for rotating said wheel upon a substantially horizontal axis, said wheel being formed in separated sections, a driving-chain passing into the space between the said sections and affording means for rotating said wheel, and means for driving said chain from a point behind said wheel.

2. In an excavator in combination, an excavating-wheel, a conveyer formed in separated sections behind said wheel, and means for driving said wheel through the space between said sections and from a point behind said conveyer.

3. In an excavator in combination, an excavating-wheel formed in sections, a conveyer behind said wheel and also formed in sections, a chain passing from a point behind said conveyer through the spaces between said sections and affording means for driving said wheel, and mechanism behind said conveyer for driving said chain.

4. In an excavator in combination, a frame, plow-beams supported at the under side of said frame and projecting forwardly

therefrom, a plow carried at the forward extremities of said beams, and adjustable hangers connecting with said beams near the forward extremities thereof and attaching to the forward extremity of said frame.

5. In an excavator in combination, a frame, inclined plow-beams pivotally attached to the under side of said frame and projecting forwardly therefrom, adjustable hangers pivotally connected with the forward extremity of said frame and pivotally attached to the forward extremities of said beams, a plow carried by said beams, an excavating-wheel before said plow and supported by said frame, and a conveyer supported at said plow and adapted to deliver material received from said wheel.

6. In an excavator in combination, a frame, inclined plow-beams projecting forwardly therefrom and pivotally attached thereto, adjustable hangers attached to the forward extremities of said beams and supported from said frame, a plow carried by said beams, arms pivotally mounted on said frame and projecting forwardly therefrom, an excavating-wheel carried between said arms, and a conveyer behind said wheel and adapted to receive material therefrom.

7. In an excavator in combination, a frame, inclined plow-beams projecting forwardly therefrom and pivotally attached thereto, adjustable hangers attached to the forward extremities of said beams and supported from said frame, a plow carried by said beams, arms pivotally mounted on said frame and projecting forwardly therefrom, an excavating-wheel carried between said arms, a conveyer behind said wheel and adapted to receive material therefrom, and means for attaching said plow to said arms.

8. In an excavator in combination, an excavating-wheel, a main conveyer adapted to receive material from said wheel, a pair of lateral conveyers disposed behind said first conveyer and adapted to receive material therefrom, bevel gear-wheels at the adjacent extremities of said lateral conveyers, and a wheel therebetween meshing therewith.

9. In an excavator in combination, excavating mechanism, a main conveyer adapted to receive material therefrom, a pair of oppositely-disposed lateral conveyers to which said main conveyer delivers, hangers adjustably supporting the outer extremities of said lateral conveyers, bevel gear-wheels at the inner extremities of said lateral conveyers and affording means for actuating the same, a double bevel-gear between said first bevel-gears and meshing with both, and means for continuously driving said last bevel-gear.

10. An excavating-wheel having a rotatable circular rim fixed heads at the extremities

of said rim inclosing the interior thereof, and teeth mounted in said rim.

11. An excavating-wheel comprising a substantially cylindrical body, removable teeth attached to the periphery of said body, heads at the extremities of said body and having openings therethrough, and covers for said openings.

12. An excavating-wheel comprising an outer rim and an inner rim, a plurality of teeth having shanks projecting through openings in said rims, and nuts on the extremities of said shanks securing the same.

13. In an excavator in combination, a pair of arms, a shaft connecting the same, a sleeve mounted on said shaft, a wheel having a body rotatably mounted on said sleeve, and a plurality of teeth carried by the periphery of said wheel.

14. In an excavator in combination, a pair of arms, a shaft connecting the same, a sleeve mounted on said shaft, a wheel having a body rotatably mounted on said sleeve, a plurality of teeth carried by the periphery of said wheel, and heads closing the extremities of said body.

15. In an excavator in combination, a pair of substantially parallel arms, a shaft connecting the same, a sleeve fixed on said shaft, a pair of concentric rims carrying teeth and constituting an excavating-wheel, and a plurality of hubs rotatably mounted on said sleeve and rigid with said rims.

16. In an excavator in combination, a pair of oppositely-disposed arms, a shaft supported therebetween, a sleeve about said shaft, a pair of rims carrying teeth and constituting an excavating-wheel, hubs rigid with said rims and rotatably mounted on said sleeve, said rims being formed in sections, a space therebetween through which a drive-chain may pass, and a chain-wheel surrounding said sleeve in said space and rigidly connecting with said rims.

17. In an excavating-wheel in combination, an outer rim having openings therethrough, an inner rim having openings therethrough, a plurality of teeth having shanks passing through said first openings and having threaded extremities passing through said last openings, said teeth having shoulders abutting the outer face of said outer rim, and nuts mounted on said extremities and securing said teeth.

In testimony whereof I have signed my name to this specification in the presence of two subscribing witnesses.

AUGUST M. ANDERSON.
